UNITED STATES PATENT OFFICE.

EMIL J. CARROLL, OF CINCINNATI, OHIO, ASSIGNOR TO THE AMERICAN LAUNDRY MACHINERY COMPANY, OF CINCINNATI, OHIO, A CORPORATION OF OHIO.

CONTROL SYSTEM FOR DRYING APPARATUS.

Application filed June 30, 1922. Serial No. 571,865.

To all whom it may concern:

Be it known that I, EMIL J. CARROLL, a citizen of the United States, residing at Cincinnati, in the county of Hamilton and State of Ohio, have invented certain new and useful Improvements in Control Systems for Drying Apparatus, of which the following is a specification.

This invention relates to a control system 10 for drying apparatus and more particularly to a system for controlling the operation of drying apparatus according to the relative humidity of the air current flowing therethrough.

15 The object of the invention is to provide an improved control system which insures uniformly reliable drying results and automatically stops the operation of the drying apparatus when the materials being dried 20 have reached such a dried condition as to bring air passing across the same to normal relative humidity, thereby doing away with the necessity of opening the machine and feeling the material being dried or running the machine for a definite time interval, usually longer than that required.

Further objects of the invention are in part obvious and in part will appear more in detail hereinafter.

30 The invention comprises the construction and arrangement of parts hereinafter described and claimed.

In the drawings, Fig. 1 is a rear elevation of one form of drying apparatus with 35 the invention applied thereto; Fig. 2 is a detail plan view on a larger scale looking down at the air outlet from the machine; Fig. 3 is a sectional elevation on the line 3—3, Fig. 1, the controlling instrument being shown for convenience in elevation; Fig. 4 is a front elevation of the controlling instrument, parts being broken away and in section to expose interior construction; Fig. 5 is an inverted sectional plan view on the 40 line 5—5, Fig. 4; and Fig. 6 is a diagrammatic view of the electrical circuits.

The invention may be applied to any form 50 of apparatus for drying any material, but particularly to drying apparatus in which materials are dried by circulating over or around the same a current of heated air to absorb and carry away moisture. The drawings show the invention applied to what is called a "drying tumbler", to wit, 55 a machine in which fabrics or clothing

which have been washed or dry cleaned and extracted to remove the greater part of the moisture or cleaning fluid are subjected to the effect of a heated air current while being agitated in said air current for removing the balance of the moisture or cleaning fluid. The particular construction and arrangement of the drying tumbler is largely immaterial. Merely for purposes of illustration the drawings show a drying tumbler 60 including a suitable hollow frame or casing 1 in which is a drying chamber 2 containing a drum 3 with foraminous walls within which the fabrics or clothing to be dried are tumbled or agitated by rotating the drum, 65 which to that end, is rotated by a suitable source of power, such as by an electric motor 4, the shaft of which is connected by suitable gearing (not shown) to the shaft 6 of the drum 3. 70

7 represents a heating chamber in which is a suitable heating device, such as steam coils or pipes 8 around which heated air flows to the channel 9 through which it is delivered to the drying chamber 2 and caused to flow through the rotating drum 80 therein. The heated air is circulated through the heating and drying chambers by the effect of a fan or blower 10, the suction side of which is connected to chamber 2 and the outlet from which communicates with a channel 11 having an outlet 85 12 to the atmosphere. Both the outer casing and the periphery of drum 3 are provided with the usual doors 13 through the 90 openings for which the materials are inserted into and removed from the drum. Fan 10 is driven in any suitable manner, such as by an electric motor 14, the shaft of which is connected by a belt 15 with the 95 shaft 16 of the fan.

In the present system the operation of the drying tumbler and more particularly the operation of either or both of the two driving motors 4, 14 is controlled by a device 100 sensitive to the relative humidity of the air current passing over or through the fabrics or clothing being dried. This instrument or controlling device is of psychrometric character and embodies the usual wet and dry bulb thermometers. The instrument itself is illustrated more particularly in Figs. 2, 4 and 5. It comprises a suitable base or frame 20 adapted for attachment 105 to the frame of the drying machine and 110

from which rises a wall 21 of insulating material. The base is shown as attached to the wall of the air current channel 11 and carried by said base and extending through said wall are protecting tubes 22 and 23, the first containing a dry bulb thermometer 24 and the second a wet bulb thermometer 25, the latter having its bulb surrounded by wick 26 dipping into reservoir 27 for liquid, such as water, which can be poured into said reservoir through a filling cup 28. The protecting tubes 22, 23 are, of course, provided with openings 29 through which the air current circulates to the thermometer bulbs. The frame of the instrument also includes a wall 30 separated from wall 21 by a side wall 31. In the cavity between said two walls are rotatable switch arms 32, 33 each having its stub shaft 34 supported by a bracket 35 attached to one end of a Bourdon tube 36, the two Bourdon tubes communicating by tubes 37 with the two thermometers. As a result each thermometer by variations in the temperature effective thereon turns its corresponding switch arm in one direction or the other. With each switch arm cooperates a yielding brush 38 by which current from the outside circuit is conducted to the switch arms. Each switch arm is provided at its free end with a contact 39 cooperating with a series of contacts, one for each arm, spaced around the arc of movement, as shown in Fig. 4. In the zone between the two sets of contacts 40 are two other sets of contacts 41, lying in straight rows, each of the contacts of said rows being connected by a wire 42 with a contact 40. Circuits are completed across contacts of the two rows 41 by a series of what may be called coupling sets or devices, to wit, two series of contacts 43 in parallel rows carried by an insulating plate 44 and coupled in pairs by wires 45. Plates 44 with its coupling sets is insertable into and removable from a recess in the front wall of the instrument and is held in place therein by a removable plate 46. With each controlling instrument there is provided a series of different plate 44 having the contacts of its two rows coupled in different ways or paired differently to correspond to different percentages of relative humidity, as will appear, so that the instrument can be made to respond to any desired percentage of relative humidity by including within it the proper one of the set of plates 44. In this respect the instrument is similar to the instrument shown and described more fully in a copending application for psychrometer, filed by myself and George W. Johnson June 14, 1922, Serial No. 568,240, to which reference may be had for a more complete description if desired.

It is obvious that since this instrument is

attached to the wall of the air current outlet with its thermometer bulbs sensitive and exposed to the air current flowing from the machine the switch arms actuated by the two thermometer bulbs will always assume positions corresponding to the characteristics of the air current to which they are subjected. The switch arm of the dry bulb thermometer will occupy a position corresponding to the normal dry bulb temperature, while the switch arm of the wet bulb thermometer will occupy a position corresponding to the evaporation point at that bulb. With each position of switch arm 32 throughout the range of its set of contacts 40 there may be a corresponding position of switch arm 33 on any one of its several contacts 40, but in each of the different positions of arm 33 the relative humidity will be different from that in any other position of said arm. In other words, relative humidity, which is actually the ratio of the percentage of moisture in the atmosphere under given conditions of temperature and pressure to the total amount of moisture that the atmosphere might possibly contain under those conditions of temperature and pressure, is usually determined by calculation from empirical tables which take into consideration the pressure and the readings of the wet and dry bulb thermometers. The present instrument is simplified by omitting consideration of variation in pressure, but takes into question variations in the wet and dry bulb thermometer readings. Each pair of positions of the two switch arms corresponds to a definite percentage of relative humidity.

Let us assume, for example, that in the instrument shown in the drawing, the several contacts 43 are cross coupled or paired by wires 45 to correspond to 30 per cent relative humidity. It is clear that if switch arm 32 stands at one of the contacts 40 at the same time that switch arm 33 stands at the one of its contacts 40 which happens to be coupled to the other contact 40 by a wire 45 a through circuit is completed between the two switch arms. This through circuit may be completed through any one of the coupling wires 45 and therefore at various normal dry bulb temperatures or at various evaporation points.

Control of the drying tumbler by the psychrometer device described is effected by circuits such as shown in Fig. 6 in which the two motors 4 and 14 are conventionally illustrated in circuit with main switches 50, 51 and the usual starting boxes 52, 53. The field of each motor has included in series therewith a retaining coil 54, said retaining coils cooperating with armatures 55 to hold the starting levers in running position. Shunted across each of the holding coils 54

is a cut out circuit 59, the two cut out circuits being normally open but adapted to be closed by a relay or switch 56 actuated by the coil 57 in a circuit 58 which circuit includes leads to the brushes 38 of the instrument shown in Fig. 4. The effect of this arrangement is as follows:

Usually at the beginning of the day the drying tumbler is operated for a few minutes without any load to cause the two switch arms to take positions corresponding to the temperature and moisture conditions in the machine. The relative humidity is determined either by calculation or by inserting 10 in succession the several plates 44 until one is found based upon the existing relative humidity, assumed here to be 30 per cent. This plate 44 is then left in the instrument. A batch of material to be dried is now placed 15 in the drying tumbler and both starting box levers are thrown over to start the motors, it being assumed that the heater is turned on so that the flowing air will be heated. Warm air is passed over the clothes so that almost 20 immediately the relative humidity of the traveling air current increases. Switch arm 32 corresponding to the dry bulb thermometer moves over due to the increase in dry bulb temperature and switch arm 33, which 25 corresponds to the wet bulb thermometer moves over due to the rise in the evaporation point. As a result the two switch arms do not occupy positions at opposite ends of the same coupling wire 45 and the circuit 30 through the coil 57 is broken. Holding coils 35 are therefore fully effective and hold the starting levers in running position. The relative humidity, of course, rises to a maximum and as the moisture is carried away begins to drop until finally a percentage of 40 relative humidity is reached corresponding to that of the particular plate 44 in the controller. When this percentage is reached a through circuit is completed across the switch 45 arms 32, 33, coil 57 is deenergized and both of the holding coils 54 are promptly short-circuited, whereupon the starting levers fly over to off position and both motors stop. When the motors stop the attendant is, of 50 course, advised that the relative humidity in the machine has reached normal atmospheric condition and the clothes are ready to be removed.

The control system described is effective 55 without the necessity of stopping the machines at intervals to test the dampness of the material by feeling it or of adopting a custom of always running the drier for a given length of time. It also insures uniform drying results because the clothes are 60 always brought to a definite dry condition.

What I claim is:

1. Drying apparatus provided with a receptacle in which the material to be dried is placed, means for conducting air through 65 said receptacle to produce a drying operation therein, and means sensitive to the humidity of the air in the receptacle for terminating the drying operation.

2. Drying apparatus, comprising a casing 70 provided with a rotary receptacle for the material to be dried, means for conducting air through said receptacle to produce a drying operation upon the material in said receptacle, and means sensitive to the humidity of the air in said receptacle for terminating 75 the drying operation.

3. Drying apparatus, comprising a drying machine in which the material to be dried is placed, means for conducting drying air 80 over the material to be dried, and means sensitive to the humidity of the air current for stopping the air conducting means when the relative humidity of the air current reaches 85 a predetermined percentage.

4. Drying apparatus, comprising a drying machine in which the material to be dried is placed, power means for conducting drying air through said machine, and means sensitive to the humidity of the air current for 90 stopping operation of said power means when the material is dried to a predetermined degree.

5. Drying apparatus, comprising a drying tumbler including a hollow drum in which the material to be dried is agitated, means for 95 rotating said drum, and means sensitive to the humidity of the air in said machine for controlling the drum rotating means.

6. Drying apparatus, comprising a drying tumbler including a rotating cylinder in which the material to be dried is agitated, means for rotating said cylinder, means for conducting air through said cylinder, and means sensitive to the humidity of the air in 100 said machine for controlling the operation of said drum rotating and air conducting means.

7. Drying apparatus, comprising a drying tumbler including a rotating drum in which the material to be dried is placed, an electric motor for rotating said drum, means for conducting a current of air through said drum, an electric motor for operating said air conducting means, means for maintaining 110 the two motor circuits in running condition, and means sensitive to the humidity of the air in said machine for controlling said maintaining means and arranged to open said motor circuits when the material 115 is dried to a predetermined degree.

In testimony whereof I hereby affix my signature.

EMIL J. CARROLL.
